[57] CLAIM

The ornamental design for a kitchen work unit, as shown and described.

DESCRIPTION

FIG. 1 is a front perspective view of kitchen work unit, showing my new design;

FIG. 2 is a front elevational view;

FIG. 3 is a left side elevational view thereof;

FIG. 4 is a right side elevational view thereof;

FIG. 5 is a top plan view thereof;

FIG. 6 is a cross-sectional view taken along line 6—6 of FIG. 2;

FIG. 7 is a rear elevational view thereof; and

FIG. 8 is a bottom plan view thereof.

The broken line showing in FIGS. 1-6 and 8 is for illustrative purposes only and forms no part of the claimed design.

FIG. 1.

FIG. 3.

FIG. 2.

FIG. 4.

FIG. 5.

FIG. 6.

FIG. 7

FIG. 8.
